(57) **CLAIM**

The ornamental design for the outer corners of a container lid, as shown and described.

DESCRIPTION

FIG. 1 is a perspective view of the outer corners of a container lid of this invention;

FIG. 2 is a top plan view thereof;

FIG. 3 is a front elevational view thereof, the rear view being identical thereto, and the right side view and the left side view being mirror images thereof.

FIG. 4 is a perspective view of the outer corners of a container lid of an alternative embodiment of this invention;

FIG. 5 is a top plan view thereof;

FIG. 6 is a front elevational view thereof, the rear view being identical thereto, and the right side view and the left side view being mirror images thereof.

FIG. 7 is a perspective view of the outer corners of a container lid of another alternative embodiment of this invention;

FIG. 8 is a top plan view thereof;

FIG. 9 is a front elevational view thereof, the rear view being identical thereto, and the right side view and the left side view being mirror images thereof.

FIG. 10 is a perspective view of the outer corners of a container lid of yet another alternative embodiment of this invention;

FIG. 11 is a top plan view thereof;

FIG. 12 is a front elevational view thereof, the rear view being identical thereto, and the right side view and the left side view being mirror images thereof.

FIG. 13 is a perspective view of the outer corners of a container lid of still another alternative embodiment of this invention;

FIG. 14 is a top plan view thereof;

FIG. 15 is a front elevational view thereof, the rear view being identical thereto, and the right side view and the left side view being mirror images thereof.

FIG. 16 is a perspective view of the outer corners of a container lid of a further alternative embodiment of this invention;

FIG. 17 is a top plan view thereof; and,

FIG. 18 is a front elevational view thereof, the rear view being identical thereto, and the right side view and the left side view being mirror images thereof.

The broken lines in the drawing depict environmental subject matter only and form no part of the claimed design.
